CLAIM

The ornamental design for a computer case, as shown and described.

DESCRIPTION

FIG. 1 is a perspective view of a computer case showing our new design;

FIG. 2 is a front elevation view thereof;

FIG. 3 is a back elevation view thereof;

FIG. 4 is left side elevation view thereof;

FIG. 5 is a right side elevation thereof;

FIG. 6 is a top plan view thereof;

FIG. 7 is a bottom plan view thereof;

FIG. 8 is a front top perspective thereof;

FIG. 9 is a back top perspective thereof;

FIG. 10 is a front elevation view thereof in exploded condition;

FIG. 11 is a front top perspective thereof in exploded condition; and,

FIG. 12 is a front bottom perspective thereof in exploded condition.

The broken lines in the drawings represent environmental subject matter and form no part of the claimed design. The inside portion of the top half of the case is unornamented and does not form part of the claimed design.
